OIL BURNER

Filed May 9, 1925

Inventor,
Paul B. Streich,
By Charles O. Sherry,
his Atty.

UNITED STATES PATENT OFFICE.

PAUL B. STREICH, OF JOLIET, ILLINOIS.

OIL BURNER.

Application filed May 9, 1925. Serial No. 29,024.

To all whom it may concern:

Be it known that I, PAUL B. STREICH, a citizen of the United States, and a resident of Joliet, Will County, Illinois, have invented certain new and useful Improvements in Oil Burners, of which the following is declared to be a full, clear, and exact description.

This invention relates to oil burners, and its principal object is to increase the efficiency of oil burners. Another object is to provide an oil burner in which practically perfect combustion takes place, whereby carbon deposits are eliminated, and whereby a maximum heat is obtained from a minimum supply of fuel. Another object is to minimize the roaring sound which usually accompanies the burning of oil in the ordinary burners.

With these and other objects and advantages in view, this invention consists in the several novel features hereinafter fully set forth and claimed.

The invention is clearly illustrated in the accompanying drawing, in which:—

Fig. 1 is a plan (partly broken out) of a burner embodying a simple form of the present invention; Fig. 2 is a vertical, cross section taken on line 2—2 of Fig. 1, and Fig. 3 is a vertical, cross section of a slightly modified form of the burner.

Referring to said drawing, and first to Figs. 1 and 2, which illustrate the preferred embodiment of the invention, the reference character 5 designates a circular cup or pan like burner body, and 6 a top plate spaced from the upper edge of the burner body 5 to leave an annular narrow discharge slot or slit 7 through which the gas is discharged.

The burner body 5 has a bottom wall 8 formed with an upstanding marginal side wall 9 which terminates at its upper edge with an inwardly projecting lip portion 10. The bottom wall 8 is also formed with an upwardly projecting annular boss 11 which, together with the side wall 9, forms an annular channel 12. The burner body 5 may be supported on a standard 13, and it is preferably formed with a hollow boss 14 that is secured upon said standard. The upper part 13^a of the standard is in the form of a pipe or conduit, which is connected to an

air supply pipe 13^b, preferably having an air register 13^c at its inlet end. By this arrangement air is admitted to the interior 55 of the burner body.

The top plate or cover 6 is preferably mounted so as to be adjustable vertically, to regulate the width of the discharge slot 7, and as shown, the top plate or cover rests 60 on threaded posts 14^a which are threadedly secured in the boss 11 of the bottom wall 8. Said top plate or cover 6 is of the same diameter as the body 5, and is formed with a centrally disposed, downwardly projecting boss 15, the lower face of which is spaced from the upper face of the boss 11. The top 6, bottom wall 8, side wall 9 and bosses 15, 11 form an annular mixing and gasifying chamber 16 into which air and atomized oil are introduced in the operation of the burner, and in which chamber 70 the atomized oil is partly consumed.

At one side, the burner body 5 is formed with a lug 17 in which is a port 17^a in 75 which is secured an oil atomizing nozzle 18. The oil supply pipe 19 is connected to the nozzle at said port and has a discharge tip 20 on its end through which oil discharges in a line at right angles to the port 17^a. 80 At one side of the oil supply pipe 19 is a compressed air pipe 21 which is connected to the nozzle and has a tip 22 that terminates at a place approximately in line with the axis of the oil supply pipe tip 20, and 85 at right angles thereto, said air tip being in alignment with the port 17^a and arranged tangentially with respect to the annular gasifying chamber 16. A pilot light tube 23 opens into the mixing chamber at one 90 side of the compressed air pipe, as shown.

Compressed air is supplied to the compressed air pipe 21, which compressed air is discharged across the discharge orifice of the oil supply pipe tip, thereby creating 95 a partial vacuum in said pipe and drawing the oil to the tip, which oil is atomized and discharged tangentially into the annular gasifying chamber 16, drawing in air through air supply pipes 13^b and 13^a. The 100 atomized oil and air whirl through the annular gasifying chamber, and when ignited by the pilot light or otherwise, are partially consumed in said chamber, and

the burning gases discharged through the slot or slit 7 into the combustion chamber of the furnace, where the burning gases come into contact with the outer air and complete combustion takes place.

An extremely hot, smokeless flame is produced, which flame is evenly distributed from the burner. Besides this, there is an economic use of oil, and the lower grades 10 may be used to an advantage. Furthermore, other volatile liquid fuels may be used in this burner, as its use is not limited to oil.

In the modified form of burner illustrated in Fig. 3, the body 5^a may be cast with the 15 top 6^a, and discharge apertures 7^a, 7^b, may be provided in the side wall, in place of the slot of the preferred form. In other respects the burner may be of the same construction as that shown in the preferred 20 form.

A burner constructed in accordance with this invention consumes all of the volatiles of the fuel, smoke is eliminated, and an extremely hot flame is produced with a minimum use of fuel.

More or less variation of the exact details of construction is possible without departing from the spirit of this invention; I desire, therefore, not to limit myself to the 25 exact form of the construction shown and described, but intend, in the following claims, to point out all of the invention disclosed herein.

I claim as new and desire to secure by 30 Letters Patent:—

1. In an oil burner, a cup like burner body, an imperforate top member therefor, said body and top member forming an annular gasifying chamber, having an annular gas discharge opening at its outer cylindrical side wall, and an atomizer nozzle 40 opening tangentially into said annular gasifying chamber.

2. In an oil burner, a cup like burner body, an imperforate top member covering said body and spaced therefrom to leave an annular gas discharge slot between the adjacent edge portions of the body and top member, said body and top member forming an annular gasifying chamber, and an atomizer nozzle discharging into, and arranged tangentially of said annular gasifying chamber.

3. In a burner, a cup like burner body 45 formed with an upstanding rim and a centrally located upstanding boss, there being

an annular channel between said rim and boss, a top plate supported above and covering said body, said top plate having a centrally located downwardly extending 60 boss, said cup and top plate forming therebetween, an annular gasifying chamber, having a discharge slot between the rim and top plate, and an atomizer nozzle opening tangentially into said annular chamber.

4. In a burner, a cup like burner body formed with an annular channel, a top plate supported above and covering said body, and forming with said body an annular gasifying chamber, there being a discharge 70 slot between the adjacent edge portions of said body and top plate, means for varying the width of said discharge slot, and an atomizer nozzle opening tangentially into said annular chamber.

5. In an oil burner, a cup like burner body, an imperforate top member therefor, said body and top member forming an annular gasifying chamber, having an annular gas discharge opening at its outer cylindrical wall, and there being an inlet port for fluid fuel, opening tangentially into said annular gasifying chamber, and there being a separate air intake, opening into said annular gasifying chamber, through its inner cylindrical wall.

6. In an oil burner, a cup like burner body, an imperforate top member therefor, said body and top member forming an annular gasifying chamber, having an annular gas discharge opening at its outer cylindrical wall, an oil atomizer nozzle discharging tangentially into said annular gasifying chamber, and there being a separate centrally located air intake, opening into said annular gasifying chamber, through its inner cylindrical wall.

7. In an oil burner, a cup like burner body formed with a centrally located upstanding boss, an imperforate top member covering said cup like member and spaced therefrom to leave a gas discharge slot at its outer side, said top member having a centrally located downwardly projecting boss, spaced away from the upstanding boss of the body to leave a passage therebetween, an oil atomizing nozzle discharging tangentially into the annular chamber formed between the body and top member, and there being a separate air inlet, opening through said upstanding boss of the body.

PAUL B. STREICH.
